UNITED STATES PATENT OFFICE.

WILLIAM F. WEGNER, OF WEST SUPERIOR, WISCONSIN, ASSIGNOR OF THREE-FOURTHS TO DANIEL E. FORD, HENRY J. CONNOR, AND HERVEY W. DIETRICH, OF SAME PLACE.

ELECTRIC-ARC LAMP.

SPECIFICATION forming part of Letters Patent No. 651,783, dated June 12, 1900.

Application filed March 12, 1900. Serial No. 8,310. (No model.)

To all whom it may concern:

Be it known that I, WILLIAM F. WEGNER, a citizen of the United States, residing at West Superior, in the county of Douglas and State of Wisconsin, have invented new and useful Improvements in Electric-Arc Lamps, of which the following is a specification.

My invention relates to electric-arc lamps; and the objects of the same are to provide simple and efficient means for automatically establishing and regulating the arc between the carbons and to provide a lamp which can be operated with either direct or alternating currents and means of adjustment which will not become deranged by currents of high voltage.

Another object is to provide a lamp which will be light in weight, not liable to get out of order, and one which may be manufactured at a comparatively slight cost.

I attain these objects by means of the construction shown in the accompanying drawings, which form a part of this specification, and in which—

Figure 1 is a vertical section of a lamp made in accordance with my invention. Fig. 2 is a perspective view of the operating mechanism.

In said drawings the numeral 1 designates the casing or dome of the lamp, and 2 is a base or support for the operative mechanism, said base or support consisting of a disk, of non-conducting material, secured within the lower end of the dome by screws 3. Fitted into a central aperture in the disk 2 is a sleeve 4, said sleeve having a flange 5 and a screw-threaded end to accommodate the nuts 6, which secure the sleeve to the disk. A tube 7 is suitably supported in an aperture near the edge of the disk 2, and said tube extends downward and at its lower end is connected to the arm or bracket which supports the lower carbon. For convenience in packing and assembling this tube may be made in two sections connected by a threaded collar 8. The lower end of the tube 7 fits an opening in the bracket 9, and a non-conducting plug 10 is fitted within the tube. A threaded bolt 11 passes through the plug 10, and a nut

12 fits the projecting end of the bolt. The 50 lower carbon is seated in a sleeve 13, insulated from the bracket 9, and is held in place by a set-screw 14. The lower carbon is designated 15 and the upper carbon 16.

Rising from the support 2 is an upright 17, 55 to the upper end of which a lever 18 is pivoted near one of its ends. To the short arm of the lever 18 a thermo-expansive wire 19 is secured, said wire extending down inside the tube 7 and connected to the upper end of 60 bolt 11. To the long arm of lever 18 a connecting-rod 20 is attached, said rod extending down and pivoted to a lever 21, pivoted on a support 22, attached to the base 2. The opposite end of lever 21 is connected to the 65 clutch 23 by a toggle 24, of dielectric material. A standard 25, extending upward from the base 2, is curved at its upper end and has secured thereto an adjusting-screw 26 for supporting a spring 27, connected at its 70 lower end to a lug 28, projecting from the clutch 23. A bracket 29 projects from the support 17, and a spring 30 is suspended from an adjusting-screw 31, passed through said bracket 29. The opposite end of the 75 spring 30 is connected to an ear 32 on an arm 33, of non-conducting material, which is connected to clutch 23. Depending from an ear 34 on arm 33 is a core 35, which extends downward into the solenoid 36, said solenoid 80 having a support 37 resting on the base 2. An adjusting-screw 38 extends upward through base 2 into the solenoid 36 and fits threads formed in support 37.

The electrical connections of my lamp are 85 made as follows: The circuit starts from the main line and connects with a resistance-coil 38, thence through wire passing through an insulating-eyelet 39 in the dome, said wire connecting with insulated clutch 23, through 90 said clutch to upper carbon 16, to lower carbon 15, through wire 40, connecting sleeve 13 and bolt 11, thence through the thermo-expansive wire 19, through wire 41, connecting top of said wire 19 and solenoid 36, through 95 solenoid-coil, through wire 42, which connects solenoid to main line, and passes through insulating-eyelet 43 in the dome.

The operation is as follows: When the current is turned through the lamp and the carbons are in contact, the entire current passes through the carbons into the thermo-expansive wire. Said wire is heated and lengthened, thus raising the short arm of lever 18 and depressing the long arm thereof, which action is communicated through connecting-rod 20 to lever 21, which permits the spring 27 to react and lift the clutch 23, thereby raising the carbon 16 and establishing an arc between the carbons. Simultaneously with this action the solenoid is energized by the current and draws down the core 35 to contact with adjusting-screw 38. This descent of the core overcomes the tension of spring 30 and draws down the clutch 23, which carries with it the upper carbon 16, thus adjusting the arc to the desired length. This action may be controlled by the adjusting-screw 38. When the arc becomes elongated by burning away of the carbons, the resistance of said arc is increased and the action of the solenoid on its core is proportionately diminished, thus permitting spring 30 to raise clutch 23, thereby releasing the upper carbon, so that it slides through the clutch to contact with the lower carbon, when the same process is gone through with again, the action of the current upon the thermo-expansive wire and solenoid 35 automatically adjusting the length of the arc.

To adapt my lamp to currents of different voltage, adjustment is made by means of screw 38.

When my device is operated in series, it is necessary to have a simple cheap resistance-coil, which may be of iron wire, in position in the normally-open shunt about the lamp in the usual way.

I am aware that the idea of regulating an arc-lamp by means of a thermo-expansive wire in combination with a floating clutch is old, having been claimed in Patent No. 219,209

and used by many subsequent inventors; but I am not aware that any one has ever used the thermo-expansive wire in combination with a floating clutch and a solenoid having an adjustable core for the purpose of regulating such a lamp, substantially as set forth in the foregoing specification.

Having thus fully described my invention, what I claim is—

1. In an electric-arc lamp, a movable carbon-holder suspended from a spring, a solenoid, a core suspended therein by a spring, and an electric circuit operating on said springs to raise one side of said carbon-holder and to lower the opposite side of said holder to clamp the carbon and establish the arc between the carbons, substantially as described.

2. In an automatic regulator for electric-arc lamps, a movable carbon-clutch, suspended by two springs at opposite sides of the clutch, a solenoid, a core suspended therein and connected to one of the springs and to the clutch, a thermo-expansive wire in electric circuit with the solenoid for depressing the core and simultaneously operating a series of levers to depress the opposite side of the clutch to establish the desired arc and said series of levers, substantially as described.

3. In a regulating mechanism for electric-arc lights, a floating clutch, a pendent spring attached to one side of said clutch, a core suspended within a solenoid attached to said spring, a second spring attached to the opposite side of said clutch, and a thermo-expansive wire connected to said second spring by suitable means, substantially as described.

In testimony whereof I have hereunto set my hand in presence of two subscribing witnesses.

WILLIAM F. WEGNER.
